LISTING ADDING MACHINE

Loring Pickering Crosman, Maplewood, N. J., assignor to Gardner Company, Orange, N. J., a corporation of Delaware

Application January 23, 1937, Serial No. 122,002

1 Claim. (Cl. 101—93)

The invention has relation to listing adding machines or the like, and more particularly to ribbon control means therefor. It has been previously proposed in the art, wherein an inked ribbon is interposed between movable type members and the usual platen roll, to rock the type bars toward the ribbon and platen, after selection has taken place and prior to a printing action.

10 It is the object of the present invention to provide means whereby the ribbon is normally held away from the platen, to facilitate insertion of the record sheet upon the platen.

15 Another object is to improve visibility of the printing line.

To provide maximum spacing between the ribbon and the platen, with a minimum of movement of the type members toward the platen, the ribbon will normally be held against the type members, and another object of the invention is to provide means whereby the ribbon will be first moved toward the platen in anticipation of a setting movement of the type members.

The invention consists in the novel construction 25 and combination of parts as set forth in the appended claim.

In the accompanying drawings, illustrating the invention:

Fig. 1 is a right side elevation of the cycle 30 control means of the machine to which the invention is applied.

Fig. 2 is a vertical section through the registering and printing mechanism.

Fig. 3 is a detail rear elevation of the ribbon 35 controlling bail and associated parts.

General operation

The adding machine to which the invention is shown as applied is of well-known construction, disclosed in its essential structure in U. S. Patent No. 1,932,013, issued October 24, 1933 to Loring P. Crosman.

For each denominational order, the machine is provided with a three-armed actuator lever, numbered 610 on the drawings, (Fig. 2) these levers being loosely mounted on a shaft 608. The forward arm of each lever 610 terminates in a segmental registering rack; the rearward arm has a lister type bar 611 pivoted thereto, and the upper arm has pivotal connection with a differential stop bar 615 cooperating with a bank of digit keys 215 to limit the movement of the lever 610.

65 The digit keys 215 which have been depressed

to represent a value are latched in depressed position with the bottoms of their stems lying in the path of movement of the related stop lugs of the bars 615, allowing said bars to advance a distance proportional to the value of the key, 5 upon operation of the machine. Depression of a digit key will also remove a column latch 214 from the path of movement of its related bar 615, these latches preventing movement of a stop bar and lever 610 in any column in which no 10 key is depressed.

A rock shaft 301 is provided with cam means 318 for governing the movement of a spring tensioned rocker frame 616, mounted on shaft 608, frame 616 carrying a series of dogs 617 normally engaged by studs 659 of the levers 610. As shaft 301 is rotated forwardly, frame 616 will be rocked, and any of the levers 610 which have been released by the depression of digit keys will be allowed to rotate, under the influence of their springs 683, until they are stopped by the lugs of bars 615 contacting the stems of the keys. Upon rearward rotation of shaft 301, the dog 617 will return the operated levers 610 to normal position. This excursion of the levers 610 serves to register amounts set in the keyboard upon one or more accumulators 403 and to set up a similar amount on the printing line of the type bars. Before the return of the operated levers 610 by the frame 616, spring type hammers 715 will be 30 released to print the item on the record sheet.

The type hammers 715 are adapted to be operated by spring actuators 700, but are normally held in tensioned position by latches 701. When a type bar is lifted, a tripping finger 702 is allowed to move into engagement with the corresponding latch 701, and at the end of the forward rotation of shaft 301, a frame upon which the tripping fingers are mounted is moved forwardly, 40 releasing the hammers from those latches which have been engaged by the fingers 702. In order to print the zero characters in the lower order places wherein no amount from 1 to 9 has been set up, the higher order latches 701 are provided with offsets 703, lying in the planes of and designed to trip the lower order latches. 45

The hammers are restored and relatched during the return rotation of shaft 301 by means of a bail 707, operated through a reciprocating cam 50 arm 303, fast to shaft 302, upon which is secured an arm 327, having link connection 321 with the reciprocating arm 316 fast to shaft 301.

Arm 316 and shaft 301 are oscillated by means of an electric motor 100 connected through a 55

clutch with a crank arm 105, connected to arm 316 by means of a connecting rod 108, so that as crank arm 105 is rotated said arm and shaft 301 will be oscillated.

5 The spring tensioned clutch pawl 153, pivotally mounted upon crank arm 105, is normally held out of engagement with a notched disk 157 (having drive connection with motor 100) by means of a lever 106 normally held in engaging position with pawl 153 by means of a latch 112. Latch 112 is controlled by means of a trigger 113, lying in the path of movement of the stem of an operating key 114. Upon depression of key 114 trigger 113 will release latch 112 and clutch lever 106 under influence of spring 111 will be pulled out of engagement with the clutch pawl 153 to start the machine in operation.

Upon release of key 114 latch 112 will return under spring action into latching position, and 20 toward the end of the cycle of operation an arm 115 connected with the crank arm 105 will contact with a tooth 116 of the clutch lever 106 and will force said lever back into latching position, bringing the end of lever 106 into the path of 25 movement of the rotating clutch member 153 to unclutch the machine.

Ribbon control (general operation)

30 Rotatably supported in a bail 304, pivotally mounted upon shaft 302 (Figs. 1 and 3) is a shaft 305 having fast thereon two opposed arms 306 and 307. Arm 306 has pin and slot engagement 308 with a lever 309, pivotally mounted upon the framing at 310, and normally held against clockwise rotation by means of a pin 324 fixed in the 35 total segment 618 which is also pivotally mounted at 310 and hereinafter to be described.

Pivoted at 311 upon the arm 307 is a slide 312 supported at its rearward end by a suitable slot 40 in projection 313 of a bracket 314 secured to fixed rod 315. Rearward end of slide 312 has engagement with a projection 317 of the ribbon support bail 300, pivotally mounted at 319 upon a bracket 320 secured to the rear framing of the 45 machine. Bail 300 is urged in clockwise rotated direction by a spring 322 and is normally held in counter-clockwise position, away from the platen 323, by the slide 312, arm 307, bail 304 (normally held against clockwise rotation by the 50 engagement of the projection 326 of said bail with arm 303), arm 306, pin 308, arm 309 and the pin 324, as shown in Fig. 1.

During the first portion of the forward stroke of arm 316 in a machine cycle, arm 303 will move 55 away from projection 326, releasing bail 304, whereupon bail 300 will rotate clockwise under influence of spring 322 to bring the ribbon 328 adjacent the platen 323. That is to say, spring 322 moves the slide 312 forwardly, the arms 306, 0 307 pivoting about point 308, and shaft 305 rocking bail 304 in a clockwise direction until stopped by engagement of a pin 329, fixed in slide 312, with the projection 313. The type bars 611 are then allowed to move to printing position in the 5 manner previously described.

Near the end of the forward stroke of arm 303 a roller 330, fixed in said arm, will engage the cam edge 331 of a bail 332, pivotally supported in the framing at 333, and impart a clockwise 0 rotative movement to said bail, rocking the type bars 611 toward the ribbon 328 and platen 323.

The hammers 715 are then tripped to print the item on the record sheet, as previously described, after which arm 303, in its return stroke, 75 will release bail 332, whereupon said bail under

influence of spring 334 will rock the type bars away from ribbon 328, prior to the restoration of said type bars, by rocker frame 616 and dogs 617, to their normal position.

Near the end of a cycle, arm 303 reengages 5 projection 326 of the bail 304 and rocks said bail in a counterclockwise direction carrying shaft 305 rearwardly, and the arm 306 being held by pin and slot connection 308, shaft 305 will also rotate clockwise, moving slide 312 rearwardly, 10 restoring bail 300 and ribbon 328 to normal position, away from the platen 323.

Ribbon control (total printing)

A total is taken by releasing the differential 15 stop bars 615, allowing them to rotate the accumulators subtractively until suitable pins 457 on the accumulator wheels contact with zero stop members 613 as hereinafter described. This will set the total in the type bars, and the hammers 20 will be tripped to print the total. The bars 615 are then reengaged with the oscillating frame and during the return stroke of said frame are moved rearwardly to normal position, the accumulators being disengaged from the 25 racks before the return stroke is made, whereby the register which has been totalized will stand at zero.

Depression of the total key 278 will not only trip the latches 214, through pin 263 and rocker 30 227, but will also trip the latch 620, by operation of a control arm 621, pivotally connected to said latch. Latch 620 normally engages a lug on total segment 618, preventing movement of said segment under the influence of the total spring 681. 35 Upon tripping of the latch, segment 618 will operate a shaft 607 having a spirally arranged row of pins 651, acting to trip the latching dogs 617 successively from right to left of the machine, the tripping of said dogs releasing the segments and also releasing stop members 613, so that they will fall into the path of the zero stops 457 on the accumulator wheels. When this zeroizing operation has progressed to the left hand side of the machine, a pin 601 fast to a 45 rearwardly extending arm of the total segment 618 will contact with a projection 602 of a rod 130 connected at its other end to latch 112, releasing said latch to start the machine. The machine being put in operation, the differential stop bars 615 will be relatched, the hammers will be tripped, and the parts restored to normal position.

Since as above described, the type bars 611 are moved to set position prior to a machine cycle of 55 operation, the following means are provided to move the ribbon 328 away from the type members before said members are set. As previously described a pin 324 mounted in total segment 618 has engagement with a projection 325 of arm 60 309, holding said member against clockwise movement under the influence of spring 322. Upon release of segment 618 pin 324 will be carried away from projection 325, releasing arm 309, whereupon spring 322 will rotate bail 300 65 clockwise to bring the ribbon 328 adjacent platen 323, the slide 312 moving forwardly and rotating arms 307, 306 about point 305.

During the forward stroke of a total cycle, segment 618 will be restored, by engagement of 70 pin 603, fast to reciprocating cam 318, with the restoral arm 604 pivotally mounted at 605 upon the segment 618. Upon return of segment 618 pin 324 will reengage projection 325 to restore arm 309. However, as previously described, arm 75

5 **303** will have released projection **326** of bail **304** and as arm **309** is caused to be rocked counter-clockwise the arms **306**, **307** will take their pivot about point **311**, rocking bail **304** clockwise about shaft **302**, the slide **312** thus remaining in forward operated position until near the completion of the cycle, when arm **303** in reengaging projection **326** will restore bail **304** and slide **312**, to again bring the ribbon to normal position, 10 shown in Fig. 1, free of the platen **323**.

10 I claim:
In a listing computing machine, the combina-

tion with operating means, printing hammers, differentially settable type bars, a platen, a ribbon guide, and an ink ribbon normally held by said guide against the type and spaced from the platen, of means engaging and normally restraining said ribbon guide but operable under control of the operating means to move the ribbon radially of and towards the platen, said operating means being timed first to control movement of the ribbon and thereafter to set the type bars 10 and to cause operation of the hammers.

5 LORING PICKERING CROSMAN.
